UNITED STATES PATENT OFFICE.

RICHARD F. LE BROcq, OF NEW YORK, N. Y., AND KARL JOHANN JULIUS SCHMUTZLER, OF NEW DORP MANOR, NEW YORK, ASSIGNORS TO LEBROcq COMPANY, OF BROOKLYN, NEW YORK, A CORPORATION OF NEW YORK.

DOOR-CLOSER.

1,143,288.

Specification of Letters Patent. Patented June 15, 1915.

Application filed October 19, 1914. Serial No. 867,303.

To all whom it may concern:

Be it known that we, RICHARD F. LE BROcq, a citizen of the United States, and a resident of the city of New York, county of Kings, 5 and State of New York, and KARL J. J. SCHMUTZLER, a citizen of the United States, and a resident of New Dorp Manor, Richmond county, New York, have invented a new and useful Improvement in Door-10 Closers, of which the following is a full, clear, and exact description.

Our invention relates to improvements in door closers and the object of our invention is to produce a simple, inexpensive and positive apparatus in which a weight is used instead of the customary spring, and in which the parts are assembled and arranged in such a manner that the operation of the device is 15 absolutely positive so that the door is sure 20 to close when it is released in an open position.

Our invention is also intended to provide a very inexpensive structure which can be easily applied to a door and an adjacent wall 25 or support, and which when used very frequently, as for instance on the door of a factory or other place, will not get out of order.

Reference is to be had to the accompanying drawings forming a part of this specification, in which similar reference characters indicate corresponding parts in all the views.

Figure 1 is a side elevation of our improved door closing apparatus as applied to a door. Fig. 2 is a sectional plan on the line 2-2 of Fig. 1, and Fig. 3 is a section on the line 3-3 of Fig. 2, showing the sliding carriage in end elevation.

The door 10 is provided with a plate 11 which connects with a pintle 12 on the rod 13, and the latter is pivoted as shown at 14 to the stud 14^a on the sliding carriage 15. Obviously the particular connection with the rod 13 is not important, as the essential thing is to have a pivotal connection by 45 means of the rod and link between the door 10 and the sliding carriage 15.

The carriage 15 is preferably formed of plates 16 and 17 which are spaced apart as 50 shown clearly in Fig. 3, and the stud 14^a on the plate 17 is recessed on the under side to form a bearing or saddle which rides on the guide rod 19. This latter is horizontally

arranged behind the door on the wall or 55 other support adjacent to the door, the guide rod having its ends inturned and secured by means of plates 20 or otherwise to the adjacent wall or support. Thus when the door is opened or closed, the carriage 15 will slide 60 horizontally on the rod 19.

Between the plates 15 and 16 of the carriage and preferably near the ends thereof, are rollers 21 which are arranged in pairs as shown clearly in the drawing, and these 65 rollers serve to prevent friction, as they are engaged by the swinging leg 22 which enters vertically between the pairs of end rollers. This leg 22 extends normally in a vertical position parallel with the back edge 70 of the door as shown in Fig. 1, and at its upper end it merges into a head 23 which is pivoted near the top as shown at 24. In the head 23 is a curved cam slot 25 which is arranged in a generally vertical position, 75 and this receives the pin 26 on the weighted arm 27, the latter extending in a generally horizontal position above the door, and being pivoted at one end as shown at 28, while its opposite or free end is provided 80 with a weight 29. Obviously the arm 27 may be made sufficiently heavy without the weight, and it is equally obvious that any suitable anti-friction devices can be used to form the cam connection between the arm 85 and the head 23.

The above described mechanism is extremely cheap and simple, and easily applied. When so applied and the door is opened, as shown by dotted lines in Fig. 2, 90 the rod 13 will push the carriage 15 along the guide rod 19, and the carriage will swing the leg 22 to the position shown by dotted lines in Fig. 1, and raise the weighted arm 27, as indicated by dotted lines in 95 same figure. When the door is released, the weighted arm 27 will by means of its pin and cam slot connection with the head 23, cause the head and leg 22 to swing toward the door, thus moving the carriage 15 and 100 closing the door by means of the connection between the carriage and the door already described.

From the foregoing description it will be seen that there is nothing to get out of order 105 about this structure, and that the parts can be cheaply made, assembled, and put in place.

We claim:—

1. A door closer comprising a sliding carriage arranged adjacent to a door, an operative connection between the carriage and the door whereby the two will move in unison, a support to guide the carriage, a swinging vertically arranged leg engaging the carriage, and a pivoted weighted arm crossing the leg and having a cam connection therewith.
2. A structure of the kind described comprising a sliding carriage, an operative connection between the carriage and the door, a horizontally arranged guiding device for the carriage, a swinging leg connected with the carriage, and a weighted arm pivoted at one end and having a cam slot and pin connection with the swinging leg.
3. A structure of the kind described comprising a horizontally arranged guide rod adjacent to the door, a carriage sliding on the rod, an operative connection between the carriage and door, a vertically arranged leg pivoted at the top and provided with a curved cam slot, and a weighted arm pivoted at one end and crossing the leg, said arm having a pin entering the aforesaid cam slot.

Copies of this patent may be obtained for five cents each, by addressing the "Commissioner of Patents, Washington, D. C."

4. A door closer comprising a horizontally arranged guide rod adjacent to a door, 30 a carriage having a saddle on one side to ride on the rod, a connection between the saddle and the door, a swinging vertically arranged leg having a free connection with the carriage, said leg having a curved cam 35 slot therein, and a weighted arm pivoted at one end and crossing the leg, said arm having a pin which enters the aforesaid cam slot.

5. A door closer comprising a horizontal 40 guide rod arranged adjacent to a door, a carriage sliding on the rod and having a door connection, said carriage comprising plates spaced apart, with rollers spaced apart between the plates, a vertically arranged swinging leg entering the carriage 45 between opposed rollers, said leg having a cam slot therein, and a weighted swinging arm crossing the leg and having a pin to enter the aforesaid slot.
